UNITED STATES PATENT OFFICE.

MAXIMILIAN KARL RINGWALD, OF AUGSBURG, AND MAX HOLLENWEGER, OF BONN, GERMANY, ASSIGNORS TO FIRM: MASCHINENFABRIK AUGSBURG-NUERNBERG, AKTIENGESELLSCHAFT, OF AUGSBURG, GERMANY, A CORPORATION OF GERMANY.

TWO-STROKE-CYCLE INTERNAL-COMBUSTION ENGINE.

Application filed February 9, 1921. Serial No. 443,723.

To all whom it may concern:

Be it known that we, MAXIMILIAN KARL RINGWALD, a citizen of the German Republic, and a resident of the city of Augsburg, 5 Germany, and MAX HOLLENWEGER, a citizen of the German Republic, and a resident of the city of Bonn, Germany, have invented new and useful Improvements in Two-Stroke-Cycle Internal-Combustion Engines, 10 of which the following is a specification.

Our invention relates to a two stroke cycle internal combustion engine with scavenging ports and to a method for the scavenging and charging the cylinders of such engines. 15 The purpose of the invention is to provide improved scavenging devices for engines having combustion chambers into which the liquid fuel is introduced after closing the exhaust ports and after compressing the 20 scavenging air. For this purpose the ports for introducing the scavenging air into the cylinder and the ports through which the burned gases escape from the cylinder are arranged in different planes. 25 The scavenging air entering through the inlet ports flows over the piston head, which is preferably hollowed out, towards the opposite side of the cylinder wall which is not pierced by exhaust ports. 30 It flows along the cylinder wall up to the cylinder cover, pressing the burned gases which move along the opposite cylinder side in the direction of the exhaust ports leaving the cylinder through the same. The ex- 35 haust and inlet ports are piston-controlled; on the down stroke of the piston first the exhaust ports and then the inlet ports are uncovered. The mixing of air and fuel takes place inside the cylinder and consequently 40 only air is introduced into the cylinder through the inlet ports. The fuel is injected into the combustion chamber after the exhaust slots have been closed and after the air in the combustion chamber of the 45 cylinder has been compressed. In consequence of the high temperature of the compressed air, combustion takes place in known

manner. The exhaust ports are distributed over a large portion of the circumference of the cylinder, that is to say over more than 50 one third. The part of the cylinder wall, to which the scavenging air current entering through the inlet slots is directed, not being perforated by exhaust ports the scavenging air flows along this side of the cylinder wall 55 in the direction of the cylinder head. The inlet slots are also distributed over more than one third of the circumference of the cylinder. They are shaped in such manner that the several currents of air entering through them unite to one current which flows in the space between the axis of the cylinder and the portion of the cylinder wall which is free from exhaust ports. The invention is applicable to single and double 60 acting two stroke cycle internal combustion engines. In cylinders with piston rods passing through the combustion chamber especially on the stuffing box end of double acting cylinders the inlet slots are arranged 65 and shaped in such manner that the currents of air entering through them pass by the piston rod and unite in the space between the piston rod and that part of the cylinder wall which is without exhaust ports and flow on 70 along the cylinder wall. The invention is equally applicable to engines of the vertical and horizontal type. 75

Figures 1 and 2 show a double acting engine according to the invention in vertical and horizontal section, respectively, Figures 3 and 4 show a slightly modified form of invention in vertical and horizontal section.

1 is the inner wall of the cylinder of a double-acting Diesel engine, 2 and 3 are the cylinder covers. 4 is the fuel valve on the cover end, 5 and 6 the fuel valves on the stuffing box end, 8 is the piston and 9 the piston rod. In the engine according to Figure 1 and 2 each inner end of the cylinder has special inlet slots 10; they are arranged in two lines one under the other. The air is introduced into the cylinder by a pump 12 through pipe 11. There are two

sets of exhaust ports 13 and 14 through which the burned gases escape from the cylinder arranged respectively above and below the air inlet ports 10. The inlet ports are distributed on the circumference of the cylinder in such a way as to occupy more than one third of the entire circumference of the cylinder and arranged so that the currents of air issuing from them, indicated in the drawing by dotted lines, unite between piston rod 9 and the cylinder wall (on the right hand side of the drawing). The exhaust ports 13 and 14 are likewise so distributed as to occupy more than one third of the circumference of the cylinder. The side of the cylinder wall opposite to the inlet and exhaust ports (on the right hand side of the drawing) is not pierced by exhaust ports. The air inlet slots 10 are distributed in two sets on the circumference of the cylinder in such a way that part of the cylinder wall is left solid. (See Figure 2.) By this disposition the currents of the scavenging air entering through the inlet slots will pass by the piston rod 9 without being deflected.

We will now proceed to describe the operation of our improved engine. On the down stroke of the piston the exhaust ports 13 and 14 are opened and the burned gases begin to escape. As the piston moves on, the inlet ports 10 are also opened and the scavenging air coming from the scavenging air pump 12 and the pipe 11 enters the cylinder. The separate currents of scavenging air flow over the piston head and unite in the space between the axis of the cylinder and that part of the cylinder wall which is not pierced by exhaust ports as shown in Figure 2, where upon the current flows along this cylinder wall. The scavenging air current indicated in the figure by dotted lines, presses the burned gases onward, which gases are flowing along the side of the cylinder wall having exhaust ports, 13 and 14 and through which they escape from the cylinder. On the back stroke of the piston the inlet ports and then the exhaust ports are closed and the air in the cylinder is compressed. Thereupon the fuel is injected through fuel valves 4 in the well known manner. At the same time the exhaust ports 14 and the inlet ports 10 of the other cylinder end are uncovered and this cylinder end is now scavenged and charged with scavenging air in the same way.

Figures 3 and 4 show the cylinder of a two stroke cycle internal combustion engine with a slightly different arrangement of the inlet slots 10. In this cylinder one set of inlet slots 10 is used in providing both the cylinder ends with scavenging air. Above and below the inlet slots are the exhaust ports 13 and 14. In all other respects the

arrangement according to Figures 3 and 4 conforms to that shown in Figures 1 and 2.

It will be observed that the piston head has a concave face, and the inlet ports are formed in such a way that the incoming scavenging air entering these ports is directed against this concave face and flows across it to the imperforate wall of the cylinder. The concavity assists in deflecting the air upwardly along the wall toward the head of the cylinder. The purpose of the entire arrangement of ports is such that a complete circuit of the scavenging air is provided for, the incoming air being in turn guided by the piston head, the wall opposite the ports, the head of the cylinder, and the other cylinder wall to the exhaust ports. Also, the arrangement of the ports is such that the exhaust ports are effectively opened prior to the opening of the inlet ports.

Having now described our invention, what we claim as new and desire to secure by Letters Patent of the United States is:

1. Two cycle internal combustion engine comprising a cylinder, a piston working therein, piston controlled exhaust ports and piston controlled inlet ports for scavenging air, said exhaust ports being effectively opened before said inlet ports, and said ports extending through only a portion of the cylinder circumference, the cylinder wall opposite said inlet ports being imperforate, means for introducing fuel into the cylinder after said exhaust ports are closed, the inlet ports being so arranged and disposed that the incoming scavenging air strikes said imperforate wall and is directed upwardly along said wall to the cylinder head, being there deflected by the cylinder head and returned to the exhaust ports, driving the burned gases before it.

2. Two cycle internal combustion engine comprising a cylinder, a piston working therein, piston controlled exhaust ports and piston controlled inlet ports for scavenging air, said exhaust ports extending through only a portion of the cylinder circumference, and being effectively opened by the movement of the piston before said inlet ports are opened, the cylinder wall opposite said inlet ports being imperforate, means for introducing fuel into the cylinder after said exhaust ports are closed, the inlet ports being so arranged and disposed that the incoming scavenging air is directed across the head of said piston to the said imperforate wall, flows upwardly along that wall toward the cylinder head, is then deflected thereby and flows downwardly to the exhaust ports, driving the burned gases to these exhaust ports and expelling them.

3. Two cycle internal combustion engine comprising a cylinder, a piston working

therein, piston controlled exhaust ports, and piston controlled inlet ports for scavenging air, said inlet ports extending through more than a third of the circumference of said cylinder, means for introducing fuel into the cylinder after said exhaust ports are closed, said exhaust ports being effectively opened before said inlet ports and extending through only a portion of the cylinder circumference, the cylinder wall opposite said inlet ports being imperforate, the inlet ports being so arranged and disposed that the incoming currents of scavenging air strike said imperforate wall whereby they are directed along that wall at one side of the cylinder axis toward the cylinder head, said current being then deflected by the cylinder head, and returned to the exhaust ports, driving the burned gases through said ports.

4. A double-acting two cycle internal combustion engine comprising a cylinder, a piston working therein, centrally disposed inlet ports in the cylinder wall, exhaust ports on one side of said inlet ports in the direction of the cylinder axis, said ports being controlled by said piston means for introducing fuel into the cylinder after said exhaust ports are closed, means for supplying scavenging air to said inlet ports, exhaust pipes in connection with said exhaust ports, said exhaust ports extending through only a portion of the cylinder circumference, the cylinder wall opposite said inlet ports being imperforate, and the inlet ports being so arranged and disposed that the incoming currents of scavenging air are directed across the face of the piston, strike the said imperforate wall, flow along that wall to the cylinder head, and are there deflected downwardly to the exhaust ports, driving the burned gases before them.

5. A double-acting two cycle internal combustion engine comprising a cylinder, a piston working therein, centrally disposed inlet ports in the cylinder wall, exhaust ports on either side of said inlet ports in the direction of the cylinder axis, said ports being arranged in planes at right angles to said cylinder axis, and being controlled by said piston, means for introducing fuel into the cylinder after said exhaust ports are closed, means for supplying scavenging air to said inlet ports, exhaust pipes in connection with said exhaust ports, said exhaust ports extending through only a portion of the cylinder circumference, the cylinder wall opposite said inlet ports being imperforate, the inlet ports being so arranged and disposed that the incoming scavenging air entering through the inlet ports flows across the cylinder head, strikes said imperforate wall and is directed upwardly along the cylinder wall to the cylinder head, being there deflected downwardly toward the exhaust ports

through which the burned gases are driven by said scavenging air.

6. Two cycle internal combustion engine comprising a cylinder, a piston working therein, piston controlled inlet and exhaust ports in the cylinder wall, said ports lying respectively in different planes, with the cylinder wall opposite said inlet ports imperforate with respect to exhaust ports, the inlet ports being uncovered by the piston subsequent to the exhaust ports, a source of scavenging air in connection with said inlet ports, the arrangement of said inlet ports being such that when these ports are opened the scavenging air entering the cylinder strikes the wall opposite the said inlet ports and is directed therealong to the cylinder head by which it is deflected in a generally downward direction to the said exhaust ports, driving the burned gases before it and expelling them through the exhaust ports.

7. Two cycle internal combustion engine comprising a cylinder, a piston working therein, piston controlled exhaust ports and piston controlled air inlet ports disposed in the cylinder wall in different planes in the direction of the cylinder axis, said exhaust ports lying nearer the cylinder head than said inlet ports and extending through only a portion of the cylinder circumference, the cylinder wall opposite said inlet ports being imperforate with respect to inlet ports whereby scavenging air entering through said inlet ports is positively guided through a complete circuit of said cylinder and is delivered to said exhaust ports, said scavenging air being guided successively by the piston head, said imperforate wall, the cylinder head, and the cylinder wall containing said exhaust ports to the latter, whereby the burned gases are expelled.

8. A two cycle internal combustion engine, comprising a cylinder, a piston working therein, exhaust ports and inlet ports for scavenging air arranged in the cylinder wall, the exhaust ports being effectively opened prior to the opening of the inlet ports, and means for introducing fuel into the cylinder after said exhaust ports are closed, the cylinder wall opposite said inlet ports being imperforate with respect to exhaust ports, and the said inlet ports being so arranged and disposed that the incoming scavenging air is directed across the piston head to said imperforate wall, flows upwardly along that wall toward the cylinder head, is deflected thereby, and then flows downwardly to the exhaust ports, driving the burned gases to these exhaust ports and expelling them.

9. A two cycle internal combustion engine, comprising a cylinder, a piston working therein, this piston having a concave head surface, exhaust ports and inlet ports for

scavenging air arranged in the cylinder wall, this wall opposite the said inlet ports being imperforate with respect to exhaust ports, and means for introducing fuel into the cylinder after said exhaust ports are closed, said inlet ports being so arranged and disposed that the incoming scavenging air is directed in a slightly downward direction and across the piston head to the said imperforate wall, flows upwardly along that wall toward the cylinder head and is then deflected thereby and flows downwardly to the exhaust ports driving the burned gases to said exhaust ports and there expelling them.
